UNITED STATES PATENT OFFICE.

CHARLES F. RANDALL, OF CHICAGO, ILLINOIS.

DUMPING MECHANISM FOR VEHICLE-CONTAINERS.

1,251,574.

Specification of Letters Patent.

Patented Jan. 1, 1918.

Application filed September 5, 1916. Serial No. 118,439.

To all whom it may concern:

Be it known that I, CHARLES F. RANDALL, a citizen of the Dominion of Canada, residing at Chicago, in the county of Cook and 5 State of Illinois, have invented certain new and useful Improvements in Dumping Mechanism for Vehicle-Containers, of which the following is a specification.

My invention relates to improvements in 10 dumping mechanisms for vehicle containers or wagon bodies.

One of the objects of my invention is to provide mechanism for dumping containers, or bodies of vehicles, which is easily operated, simple and inexpensive in construction and which is so arranged that the container when returned to normal position is supported at four points, at least, on the frame without imposing all of its weight 20 upon the dumping mechanism, at any time.

Another object of my invention is to provide a dumping mechanism whereby the hopper, other receptacle, or body, is inseparably attached to the supporting frame, 25 and another object is to provide an automatic lock, to restrain the mechanism, to prevent its movement when the receptacle is in its normal position.

Other and further objects of my invention 30 will become readily apparent, to persons skilled in the art, from a consideration of the following description when taken in conjunction with the drawings, wherein:

Figure 1 is an end elevation of the device 35 showing the hopper-like receptacle by dotted lines in dumping position, and by full lines in normal position.

Fig. 2 is a side elevation showing parts in section.

40 In both views the same reference characters are employed to indicate similar parts.

In the particular embodiment illustrated herein, I have shown the dumping mechanism applied to a side dumping container 45 and I have shown it adapted to be dumped upon either side. It is evident, however, that the same mechanism may be employed for dumping the contents of the receptacle at the end or rear of the vehicle, in which 50 event the dumping mechanism moves the hopper or body only in one direction, from its normal position.

The two end frames 5 and 6, which are 55 substantially duplicates of each other, are mounted upon a base 7. Each end frame is provided with a rack 8, parallel with,

but below the slot 9. A semi-ovate wing or frame 10 extends vertically from the frames 5 and 6 and through these wings, nearer to the respective body parts of the end frames, 60 the slightly curved slot 9 is made. Extending laterally from the wing 10 is a flange 11 which substantially overlies or projects into a vertical plane including the outer edge of the rack 8. This flange affords 65 means for protecting the rack from falling dirt or dust.

A hopper 12 is provided, at each end, with an outwardly extending flange 13 and is mounted upon a shaft 14, said shaft being located below the center of gravity of 70 said hopper. The shaft extends through the slots 9—9 and beyond the frames 5 and 6 and includes on each end a roller disk 15 and a geared pinion 16. The roller disks 75 15—15 each tracks in a space between the rack 8 and the wing 10 on the flange 13. These rollers bear the weight of the hopper or receptacle 12, when the said receptacle is being moved into dumping position. On 80 either of the outer ends of the shaft 14 is a crank lever 17, for rotating the shaft in the act of dumping the contents of the receptacle 12. Located around the edge of the frame or wing 10 are a series of rollers 18, 85 19, 20 and 21. These rollers are preferably mounted upon arms 22 that are slidably adjustable between ribs 23. The rollers 19 and 20, of which there are two of each, one at each end, underlie the flanges 13—13 of 90 the hopper, or body, and support the outer corners of same when it is in normal position, as shown by the full lines in Fig. 1. The hopper, or receptacle, cannot be moved from this position of rest unless the shaft 95 14 be rotated. Projecting from the shaft 14, as an integral extension of the crank arm 17, is an arm 24 pointed, at its outer end, and adapted to engage a spring latch 25. The spring latch by this means holds 100 the shaft 14 against rotation while the receptacle, or hopper 12, is supported by the rollers 19 and 20 upon the frame or wing 10 of the end frames 5 and 6.

To dump the hopper it is only necessary 105 to rotate the crank arm 17, after raising the latch 25 to permit the free rotation thereof. The dotted lines show that the crank arm 17 has rotated to the terminal of the slots 9—9 to the left and that the hopper 12 has moved 110 into dumping position. In the particular exemplification shown, the hopper 12 may

be dumped on the right side when the crank arm 17 is rotated toward the right or on the left side when the crank is rotated in that direction. In returning the hopper to the 5 normal position, from dotted line or dumping position, the flanges 13-13 of the hopper engage the rollers 18 or 21, as the case may be, below a line drawn through the 10 transverse center of the hopper, when the hopper is in dumped position, causing the 15 hopper to ride upon these guide rollers until it reaches a position where the flanges 13-13 ride upon the rollers 19-19 or 20-20, as the case may be, after which, upon 20 further rotation of the crank arm 17, the hopper will be brought to upright position as shown in full lines in Fig. 1, with the flanges 13-13 resting upon the central, upper surface of the wings 10, with the outer 25 ends of the flanges 13-13 resting upon the rollers 19-19 and 20-20, thus holding the hopper firmly in place, against possibility of displacement, except by rotation of the crank arm 17 or the shaft 14. The shaft 14 transmits the power from the crank arm 30 from the frame 5 to a geared pinion 16, which is associated with the frame 6 by means of racks 8-8 which are parts of the respective frames 5 and 6. The frames 5 35 and 6 are substantial duplicates and the dumping mechanism, shown in cross section on the left side of Fig. 2 is substantially duplicated on the right side, with the exception that the crank arm is shown on the left side end but it may as conveniently be located interchangeably on the right side end of the shaft 14.

The apparatus heretofore described shows how the mechanism for dumping the vehicle 40 receptacle may be employed for dumping on either one or the other of the sides of the vehicle but it is manifest that without material change the same mechanism may be employed for dumping the receptacle at the 45 rear of the vehicle, when desired, in which latter event the mechanism will dump in one direction only.

Having described my invention, what I claim is:

50 1. In an apparatus of the character described the combination of two stationary

end frames, a rack on each frame; a receptacle positioned between the frames, a shaft extending through the receptacle and journaled therein, a pinion on each end of the 55 shaft for engagement with the adjacent racks, means for rotating the shaft, flanges projecting outwardly from each end of the receptacle and positioned to bear upon the upper edges of the frames when the receptacle is in its normal position, and rollers carried by each frame for engagement with the flanges when the receptacle is moved from normal position.

2. In an apparatus of the character described the combination of two stationary end frames having slots in substantially the same horizontal plane, a rack on each frame, adjacent the slot, a receptacle positioned between the frames, a shaft extending through the receptacle and journaled therein, its end portions extending through the slots in the frames, a pinion on each end of the shaft for engagement with the adjacent racks, means rotating the shaft, flanges projecting 75 outwardly from each end of the receptacle and positioned to bear upon the upper edges of the frames when the receptacle is in its normal position, and rollers carried by each frame for engagement with the flanges when 80 the receptacle is moved from normal position.

3. In an apparatus of the character described the combination of two stationary end frames, a rack on each frame; a receptacle positioned between the frames, a shaft extending through the receptacle and journaled therein, a pinion on each end of the shaft for engagement with the adjacent 85 racks, means for rotating the shaft, flanges 90 projecting outwardly from the upper edges of each end of the receptacle, and rollers carried by the frames for coöperation with the flanges.

In testimony whereof I hereunto set my 95 hand in the presence of two subscribing witnesses.

CHARLES F. RANDALL.

In the presence of—

STANLEY W. COOK,
LORETTA A. GIBBONS.
